(57) **CLAIM**

The ornamental design for jewellery, as shown and described.

DESCRIPTION

1. Jewellery

1.1 : Perspective

1.2 : Front

1.3 : Back

1.4 : Right

1.5 : Left

1.6 : Top

1.7 : Bottom

1.8 : Enlarged

The product is an item of jewellery such as a bracelet, necklace, or ring; the present design relates to an item of jewellery for adornment of a person and results from the shape of the product as represented in the annexed drawings, which is best illustrated in the front perspective view of fig.1.1.

The broken lines in FIG. 1.8 show the boundaries of an enlarged portion of the jewellery item and form no part of the claimed design.

1 Claim, 8 Drawing Sheets
